CLAIM

We claim the ornamental design for a riflescope, as shown and described.

DESCRIPTION

FIG. 1 is a side perspective view of a riflescope showing our new design.

FIG. 2 is a front elevation view of the riflescope of FIG. 1; FIG. 3 is rear elevation view of the riflescope of FIG. 1; FIG. 4 is a right side elevation view of the riflescope of FIG. 1;

FIG. 5 is a left side elevation view of the riflescope of FIG. 1; FIG. 6 is a top view of the riflescope of FIG. 1; and, FIG. 7 is a bottom view of the riflescope of FIG. 1. The broken lines in FIGS. 1, 2, 4, 5, and 7 show portions of the riflescope that form no part of the claimed design.
